LIQUID INLET AND ANTIBACK-SIPHONING
FIXTUREFrank D. Low, La Grange Park, Ill., assignor to
General Electric Company, a corporation of
New York

Application April 21, 1950, Serial No. 157,362

7 Claims. (Cl. 134—182)

1

The present invention relates to a vat and a combination liquid inlet and anti-back-siphoning fixture, and more particularly to the combination of a vat and a fixture of the character noted incorporated in dishwashing apparatus of the front opening type.

Dishwashing apparatus of the front opening type conventionally comprises an upstanding cabinet, an upstanding vat housed in the cabinet, a front door mounted for movements between open and closed positions with respect to aligned front openings respectively provided in the front of the cabinet and in the front of the vat, inlet valve mechanism for controlling the introduction of hot washing liquid into the upper portion of the vat, drain valve mechanism for controlling the drainage of the hot washing liquid from the lower portion of the vat, and impeller mechanism for circulating the hot washing liquid in the vat when the front door occupies its closed position. The inlet valve mechanism is connected to a suitable source of hot washing liquid, such, for example, as a hot water tank that is normally connected to the public or city water mains; and the drain valve mechanism is connected to drain plumbing that is normally connected to the public or city sewerage system. Ordinarily in the dishwashing apparatus, the dishes, and the like, that are to be washed are supported upon an open wire-work rack that is movable into and out of the vat through the aligned front openings when the front door occupies its open position. Usually in the dishwashing apparatus, the hot water is introduced into the upper portion of the vat and projected downwardly through the rack in the form of a spray by a spinner device mounted just below the top wall of the vat; while the impeller mechanism is mounted just above the bottom wall of the vat and directs the hot water upwardly in the form of a rotary swirl through the rack into bombarding relation with the dishes supported by the rack and toward the top wall of the vat, the hot water returning toward the bottom wall of the vat by the action of gravity. Finally, the dishwashing apparatus may comprise an electric heater, and an electric program control device that selectively governs the different elements thereof to provide an automatic timed cycle of operation including washing, rinsing and drying steps.

Occasionally, the supply of water from the city mains fails so that instead of the normal condition of a gauge pressure in the city water mains, the abnormal condition of a subatmospheric pressure appears in the city water mains, causing a

2

back-suction or back-siphon action from the hot water tank into the city water mains and consequently from the inlet valve mechanism of the dishwashing apparatus into the hot water tank, whereby there is the possibility of back-siphoning from the upper portion of the vat of the dishwashing apparatus through the hot water tank into the city water mains, should it happen that the inlet valve mechanism occupies its open position at the time that the back-siphoning effect occurs in the city water mains. Should this happen, it is apparent that the supply of water in the city water mains might be contaminated with the hot water that is being circulated in the vat of the dishwashing apparatus, which circulated hot water not only contains detergent but certain dissolved impurities and foreign matter that has been washed from the dishes that are undergoing the washing process in the vat of the operating dishwashing apparatus.

In order to safeguard the public health and to insure that the water in the city water mains is not contaminated in the manner described above, certain cities have adopted plumbing codes or regulations that require the installation into the plumbing connections between the hot water tank and the dishwashing apparatus of a vacuum breaking or anti-back-siphoning device.

These plumbing code requirements not only complicate the plumbing of the dishwashing apparatus, but they render it necessary for the plumber to stock or acquire the special anti-back-siphoning device and to find some hidden place in the plumbing connections in which the device may be inserted. The latter requirement is often very difficult when the kitchen space is rather small, as in the case of apartment buildings and the like.

Accordingly, it is a general object of the present invention to provide in dishwashing apparatus of the character described, a built-in combination liquid inlet and anti-back-siphoning fixture or device that fully satisfies the requirements of the plumbing codes mentioned, so that the installation of the dishwashing apparatus necessitates no special external device or apparatus.

Another object of the invention is to provide the combination of a vat, or the like, and a combination liquid inlet and anti-back-siphoning fixture that is so constructed and arranged that the possibility of back-siphoning from the vat into the liquid supply system preceding the fixture is positively eliminated.

55 A further object of the invention is to provide

a combination liquid inlet and anti-back-siphoning fixture of improved and simplified construction and arrangement.

Further features of the invention pertain to the particular arrangement of the elements of the dishwashing apparatus and the combination liquid inlet and anti-back-siphoning fixture, whereby the above-outlined and additional operating features thereof are attained.

The invention, both as to its organization and method of operation, together with further objects and advantages thereof, will best be understood by reference to the following specification taken in connection with the accompanying drawings, in which Figure 1 is a fragmentary side elevational view, partly broken away, of dishwashing apparatus comprising a vat and a combination liquid inlet and anti-back-siphoning fixture, and embodying the present invention; Fig. 2 is a plan view, partly in section, of the dishwashing apparatus, the section being taken in the direction of the arrows along the offset line 2—2 in Fig. 1; Fig. 3 is an enlarged fragmentary plan view, partly broken away, of the top wall of the vat and the fixture incorporated in the dishwashing apparatus shown in Figs. 1 and 2; Fig. 4 is an enlarged side elevational view, partly in section, of the fixture shown in Fig. 3, the section being taken in the direction of the arrows along the offset line 4—4 in Fig. 3; Fig. 5 is an enlarged fragmentary vertical sectional view of the partition and the combination nozzle and baffle element incorporated in the casing of the fixture shown in Figs. 3 and 4; Fig. 6 is an enlarged vertical sectional view of the top wall of the vat and a modified form of the combination liquid inlet and anti-back-siphoning fixture, and embodying the present invention; Fig. 7 is an enlarged plan view, partly in section, of the fixture shown in Fig. 6, the section being taken in the direction of the arrows along the line 7—7 in Fig. 6; Fig. 8 is an enlarged fragmentary bottom view of the fixture shown in Figs. 6 and 7; Fig. 9 is an enlarged vertical sectional view of the top wall of the vat and another modified form of the combination liquid inlet and anti-back-siphoning fixture, the section being taken in the direction of the arrows along the line 9—9 in Fig. 10, and embodying the present invention; and Fig. 10 is an enlarged plan view of the fixture shown in Fig. 9. In the drawings, the fixture shown in Figs. 3 to 5, inclusive, and the fixture shown in Figs. 6 to 8, inclusive, are drawn at an enlarged scale, while the fixture shown in Figs. 9 and 10 is drawn at approximately actual scale.

Referring now to Figs. 1 and 2 of the drawings, the dishwashing apparatus 11 there illustrated, and embodying the features of the present invention, is of the general character of that disclosed in the copending application of Edgar S. Stoddard, Serial No. 105,613, filed July 19, 1949, and comprises an upstanding outer cabinet 12, housing an upstanding vat 13. The cabinet 12 includes top and bottom walls 14 and 15, front and rear walls 16 and 17, and opposed side walls 18 and 19. The front wall 16 is provided with a laterally extending and rearwardly offset toe-receiving recess 20 adjacent to the lower portion thereof and a front opening 21 that is laterally offset toward the righthand wall 19. The vat 13 comprises top and bottom walls 22 and 23, a rear wall 24, and opposed wide walls 25 and 26. The bottom wall 23 has a substantial centrally disposed sump 27 formed therein, and the top wall 22, the bottom wall 23, and the side walls 25

and 26 terminate in an outwardly directed front doorway or opening 28 that is aligned with respect to the front opening 21 formed in the front wall 16.

Further, a front door 29 is mounted upon the lower portion of the doorway 28 for movements between closed and open positions with respect to the front opening 21 and into and out of the doorway 28. The front door 29 carries a handle 30 adjacent to the upper end thereof in order to facilitate the movements thereof, and is provided with structure 31 in the upper edge thereof that accommodates ventilation of the interior of the vat 13 through the doorway 28 and the front opening 21 adjacent to the top of the front wall 16. Also vapor directing structure 32 is carried upon the upper portion of the front wall 16 for the purpose of guiding and projecting the vapor out of the top of the doorway 28 and to the exterior, as disclosed in the Stoddard application mentioned. The front door 29 is of the gasketless type and cooperates with the front doorway 28 and the wall structure of the vat 13 in order to prevent the escape of the washing liquid from the vat 13 during the operation of the dishwashing apparatus 11.

Further, the dishwashing apparatus comprises inlet valve mechanism 33 that is connected by way of an inlet pipe 34 to a suitable source of hot water, such for example, as a hot water tank, the hot water tank, not shown, being normally connected to the city water mains so that hot water may be supplied under gauge pressure to the inlet valve mechanism 33. Further, the inlet valve mechanism 33 is connected by an inlet conduit 35 extending between the side walls 18 and 25 and between the top walls 14 and 22, to a combination liquid inlet and anti-back-siphoning fixture 36, the fixture 36 being arranged between the top walls 14 and 22 and carried by an upwardly directed substantially centrally disposed square boss 22a provided in the top wall 22, and communicating with the upper portion of the vat 13 in a manner more fully explained hereinafter. It will be understood that the inlet valve mechanism 33 is of the solenoid-controlled type and is operative between closed and open positions so that the hot water may be introduced into the upper portion of the vat 13 by the fixture 36, when the inlet valve mechanism 33 occupies its open position. Preferably the inlet valve mechanism 33 is of the fast-opening and slow-closing type in order to eliminate water hammer in the connected plumbing extending back to the hot water tank. Further, the dishwashing apparatus 11 comprises drain valve mechanism, not shown, that is operatively connected between the sump 27 of the vat 13 and the drain plumbing extending back to the city sewerage system. Preferably this drain valve mechanism, not shown, is of the solenoid-controlled type including open and closed positions so that the washing liquid may be selectively retained in the sump 27 when the drain valve mechanism occupies its closed position.

Further the dishwashing apparatus 11 comprises liquid circulating mechanism that may take the form of a motor-driven impeller 37 mounted for rotation adjacent to the bottom wall 23 within the sump 27. Finally, the dishwashing apparatus 11 may comprise an electric heating element 38 of the sheathed electric resistance conductor type arranged in the lower portion of the vat 13 and surrounding the impeller 37, as well as a program selector switch 39 mounted

upon the front wall 16 and disposed between the side walls 18 and 25.

In view of the foregoing general description of the dishwashing apparatus 11, it will be understood that the program selector switch 39 is controllable to produce an automatic timed operating cycle including washing, rinsing and drying steps. In the operation of the dishwashing apparatus 11, when the inlet valve mechanism 33 occupies its open position, hot water is supplied to the fixture 36 and introduced into the upper portion of the vat 13, the hot water being directed downwardly therethrough and accumulating in the sump 27 when the associated drain valve mechanism, not shown, occupies its closed position. On the other hand, when the drain valve mechanism, not shown, occupies its open position, the hot water accumulating in the sump 27 is drained therefrom into the associated drain plumbing. During the normal operation of the dishwashing apparatus 11, a motor, not shown, drives the impeller 37 so that the hot water accumulating in the sump 27 is thrown upwardly with a swirl toward the upper portion of the vat 13. Normally the dishes and other utensils that are to be washed are supported within the vat 13 upon a rack of open wire-work construction, not shown, the rack being movable into and out of the vat 13 through the front doorway 28 when the front door 29 occupies its open position. During the drying step of the dishwashing apparatus 11, the drain valve mechanism, not shown, is operated into its open position while the inlet valve mechanism 33 occupies its closed position, and an electric circuit, not shown, is completed for supplying energy to the electric heater 38, while the impeller 37 is operated; whereby heated air is blown upwardly through the rack, not shown, and circulated in the vat 13 for the purpose of drying the dishes supported by the rack.

Referring now to Figs. 3 to 5, inclusive, the construction and arrangement of the fixture 36, embodying the features of the present invention, is disclosed in detail and comprises an upstanding substantially cylindrical casing 40 terminating adjacent to the lower portion thereof in a substantially cylindrical downwardly extending projection 41. The projection 41 is arranged in an opening 22b formed in the central portion of the boss 22a provided in the top wall 22 of the vat 13; and a liquid-tight connection is made between the casing 40 and the adjacent portion of the boss 22a by an arrangement including upper and lower resilient gaskets 42 and 43 surrounding the opening 22b and respectively arranged above and below the boss 22a. Also a metallic pressure ring 44 engages the gasket 43; and the assembly is retained in place by a nut 45 that is threaded upon the exterior surface of the projection 41. Thus the lower end of the projection 41, as well as the nut 45, the pressure ring 44, and the gasket 43 are disposed below the top wall 22 and within the upper portion of the vat 13.

The casing 40 is hollow and is provided with a substantially annular flange 46 adjacent to the upper end thereof that is employed for the purpose of securing in place an associated cap 47 that is provided with a substantially annular flange 48 adjacent to the lower portion thereof. The cap 47 is of hollow construction and is secured in liquid-tight relation to the upper end of the casing 40 by an arrangement including a partition or diaphragm 49 and an associated

gasket 50, as well as a plurality of screws 51 extending through openings provided in the flange 48 and threaded into aligned openings provided in the flange 46. More particularly the upper end of the casing 40 provides a substantially flat annular surface 52 that engages and supports the adjacent annular portion of the partition 49, and the lower end of the cap 47 is provided with a substantially annular shoulder 53 that engages the adjacent gasket 50. Thus it will be understood that the partition 49 divides the interior of the casing 40 and the cap 47 into an upper chamber 54 and a lower chamber 55, the chambers 54 and 55 being disposed primarily respectively within the cap 47 and within the casing 40.

The central portion of partition 49 is upwardly offset, as indicated at 56, and is provided with a centrally disposed hole 57 in which there is located and rigidly secured in place a substantially cylindrical element 58. The element 58 is of one-piece construction and includes an upper nozzle part 59 disposed within the chamber 54 and a lower baffle part 60 disposed within the chamber 55, the parts 59 and 60 being secured together by a pair of bridging lugs 61 formed integrally therewith and extending therebetween, whereby the parts 59 and 60 are separated from each other by two opposed slots 62. The nozzle part 59 is hollow and provided with a predetermined internal diameter; and likewise, the baffle part 60 is hollow and provided with a predetermined internal diameter. The internal diameter of the baffle part 60 is somewhat larger than that of the nozzle part 59, for a purpose more fully explained hereinafter.

Also the central portion of the cap 47 comprises a downwardly projecting hollow stud 63 extending into the nozzle part 59 and cooperating therewith to define a substantially cylindrical nozzle passage 64 therebetween that communicates directly with the chamber 54. Further the interior surface of the cap 47 is provided with an annular recess 65 in order to afford a direct and free communication between the chamber 54 and the nozzle passage 64. A substantially cylindrical hole 66 is formed in the projection 41 and communicates directly between the lower portion of the chamber 55 and the upper portion of the vat 13; and a substantially vertically disposed shaft 67 is arranged within the casing 40 and projects through the hole 66 into the upper portion of the vat 13. Specifically the upper end of the shaft 67 is threaded, as indicated at 68, and engages the threaded interior of the hollow stud 63 carried by the cap 47. Thus the shaft 67 is disposed centrally in the cap 47 and the casing 40 and projects downwardly from the stud 63 through the baffle part 60 in spaced relation therewith and thence through the chamber 55 and the hole 66. The lower end of the shaft 67 is arranged within the upper portion of the vat 13, as previously noted, and has mounted thereupon, a spinner member 69 formed of molded rubber, or the like. The spinner 69 is mounted for rotation on the extreme lower end of the shaft 67 and comprises a substantially annular body portion 70 carrying a plurality of substantially radially disposed and curved blades 71.

Also the cap 47 is provided with a substantially tubular inlet connection 72 communicating with the chamber 54 and into which one end of the inlet conduit 35 is secured in liquid-tight relation. In a similar manner, the casing 40 is provided with a tubular vent connection 73 com-

municating with the chamber 55 and supporting the inner end of a vent conduit 74, the outer end of the vent conduit 74 extending laterally over the top wall 22 of the vat 13 and being turned downwardly, as indicated at 75, between the sidewalls 18 and 25 in the dishwashing apparatus 11. The outer downwardly turned end 75 of the vent conduit 74 terminates just below the top wall 22 and communicates directly with the atmosphere. Thus the vent connection 73 provides a vent passage 76 extending through the vent conduit 74 and communicating between the chamber 55 and the atmosphere. The cylindrical nozzle passage 64 is arranged above and in vertical alignment with the cylindrical opening through the baffle part 60 through which the shaft 67 extends; and also the cylindrical nozzle passage 64 is arranged above and in alignment with the hole 66 provided in the projection 41; and the spinner 69 is located directly below the hole 66 and in alignment with the nozzle passage 64.

In view of the foregoing description of the construction and arrangement of the fixture 36, it will be understood that when the inlet valve mechanism 33 in the dishwashing apparatus 11 is operated into its open position that hot water is supplied from the inlet pipe 34 into the inlet conduit 35 under gauge pressure and thence into the communicating chamber 54. The hot water in the chamber 54 passes upwardly and thence downwardly into the cylindrical nozzle passage 64 between the nozzle part 59 and the stud 63; whereby a substantially annular stream of hot water is formed and projected downwardly around the shaft 67. The defined stream of hot water passes from the cylindrical nozzle 64 downwardly through the baffle part 60, the chamber 55 and the hole 66 into the upper portion of the vat 13, whereupon it impinges upon the spinner 69 causing the spinner 69 to be rotated rapidly. The rotating spinner 69 breaks-up the stream of hot water and spreads it out and projects it in the form of a downwardly and outwardly directed whirling spray into the upper portion of the vat 13 and through the rack arranged in the vat 13 and supporting the dishes that are to be washed. The defined hot water stream projected through the chamber 55 around the shaft 67 passes well inwardly with respect to the inner end of the vent passage 76 in order to prevent the escape of hot water from the chamber 55 through the vent passage 76 and consequently through the vent conduit 74 to the exterior. Also, it will be understood that the defined stream of hot water surrounding the shaft 67 and projected through the hole 66 is effective substantially to prevent vapor or steam in the vat 13 from escaping upwardly into the chamber 55 and thence into the vent passage 76. Moreover the arrangement of the spinner 69 upon the lower end of the shaft 67 is useful in limiting the amount of vapor or steam that can escape from the vat 13 into the chamber 55 and thence into the vent passage 76, when the inlet valve mechanism 33 occupies its closed position.

In the operation of the fixture 36, it will be understood that the pressure head in the chamber 54 is converted into a velocity head in the nozzle passage 64 in a well-known manner, whereby the stream of hot water passing through the baffle part 60 is well-defined; however, the baffle part 60 surrounding the stream of hot water intercepts any spread of the stream and prevents the hot water from escaping from the chamber

55 into the inner end of the vent passage 76 and consequently into the vent conduit 74.

Further considering the operation of the fixture 36 and assuming that the abnormal condition of the subatmospheric pressure appears in the inlet conduit 35, the subatmospheric pressure appears in the chamber 54 causing a back-suction through the nozzle passage 64 from the chamber 55. However, no substantial vacuum is drawn in the chamber 55 since the vent passage 76 is of ample cross-section and communicates directly via the vent conduit 74 with the atmosphere, whereby air is drawn into the vent conduit 74 and passes via the vent passage 76 into the chamber 55. The air thus delivered into the chamber 55 passes both through the space between the baffle part 60 and the shaft 67 and through the slots 62 directly into the nozzle passage 64 and thence into the chamber 54 and consequently into the inlet conduit 35, thereby substantially relieving the subatmospheric pressure therein. In any case, this venting of the chamber 55 via the vent passage 76 prevents any material back-siphoning through the hole 66, thereby positively eliminating the possibility of back-siphoning of hot water from the upper portion of the vat 13 into the inlet conduit 35 and thence through the connected hot water tank into the city water mains.

In the construction of the fixture 36, the vertical distance between the lower end of the nozzle part 59 and the lower portion of the vent passage 76 at the inner end of the vent conduit 74 must be at least 1" in order to comply with the usual city plumbing code requirements. Since the vertical distance between the top walls 14 and 22 is quite limited, the fixture 36 must be of compact construction, and in order to obtain the vertical distance of 1" previously noted, the partition 49 is upwardly directed, as indicated at 56, adjacent to the central portion thereof, as previously noted; and the slots 62 are provided between the nozzle part 59 and the baffle part 60.

In view of the foregoing description of the construction of the fixture 36, it will be understood that the cap 41 may be readily placed and removed with respect to the casing 40 by proper manipulation of the screws 51, the inlet conduit 35 being formed of copper or other flexible material to permit the relative movements required. Also the casing 40 may be readily placed and removed with respect to the opening 22b formed in the top wall 22 by proper manipulation of the nut 45; and the spinner 69 may be readily placed and removed with respect to the lower end of the shaft 67. After the cap 41 has been removed from the casing 40, the partition or diaphragm 49 may be readily placed and removed with respect to the upper end 52 of the casing 40. Preferably the metal parts of the fixture 36, including the casing 40, the cap 41, the nut 45, the vent conduit 74, the partition 49, the element 58, and the screws 51 are formed of copper or brass or other copper alloys; while the shaft 67 may be formed of a noncorrosive alloy of steel.

Referring now to Figs. 6 to 8, inclusive, the modified form of the fixture 136 there illustrated, and embodying the features of the present invention, comprises an upstanding substantially cylindrical casing 140 terminating adjacent to the lower portion thereof in a substantially cylindrical downwardly extending projection 141. The projection 141 is arranged in the opening 22b formed in the central portion of the boss

22a provided in the top wall 22 of the vat 13; and a liquid-tight connection is made between the casing 140 and the adjacent portion of the boss 22a by an arrangement including upper and lower resilient gaskets 142 and 143 surrounding the opening 22b and respectively arranged above and below the boss 22a. Also a metallic pressure ring 144 engages the gasket 143; and the assembly is retained in place by a nut 145 that is threaded upon the exterior surface of the projection 141. Thus the lower end of the projection 141, as well as the nut 145, the pressure ring 144 and the gasket 143 are disposed below the top wall 22 and within the upper portion of the vat 13.

The casing 140 is hollow and provided with a substantially annular flange 146 adjacent to the upper end thereof that is employed for the purpose of securing in place an associated cap 147 that is provided with a substantially annular flange 148 adjacent to the lower portion thereof. The cap 147 is of hollow construction and is secured in liquid-tight relation to the upper end of the casing 140 by an arrangement including a partition or diaphragm 149 and an associated gasket 150, as well as a plurality of screws 151 extending through openings provided in the flange 148 and threaded into aligned openings provided in the flange 146. More particularly, the upper end of the casing 140 provides a substantially flat annular surface 152 that directly engages and supports the adjacent annular portion of the partition 149; and the gasket 150 is arranged directly between the annular portion of the partition 149 and the marginal flange 148 provided on the cap 147. Thus it will be understood that the partition 149 divides the interior of the casing 140 and the cap 147 into an upper chamber 154 and a lower chamber 155, the chambers 154 and 155 being disposed primarily respectively within the cap 147 and within the casing 140. The central portion of the partition 149 is upwardly offset, as indicated at 156, and terminates in an upwardly directed tube 157 extending well into the chamber 154 and disposed in vertical alignment with respect to a hole 158 formed in the projection 141 and communicating between the chamber 155 and the upper portion of the vat 13. A stream-forming element 159 is arranged in the tube 157 and provides a communication between the chambers 154 and 155.

The cap 147 is provided with an inlet connection terminating the inlet conduit 35; and the casing 140 is provided with a vent connection 160 affording a vent passage 161 and supporting a vent conduit 162 so that the vent passage 161 communicates between the chamber 155 and the atmosphere. Finally the nut 145 carries a substantially annular deflector 163 disposed therebelow and connected thereto by a pair of spaced-apart arms 164. Preferably the nut 145, the deflector 163 and the arms 164 are formed of one-piece construction, whereby a pair of oppositely directed exit slots 165 are provided adjacent to the opposite sides of the deflector 163.

The operation of the fixture 136 is substantially identical to that of the fixture 36, previously described; and it will be understood that the hot water that is supplied via the inlet conduit 35 into the chamber 154 is projected by the stream-forming element 159 through the tube 157 in a well-defined stream and thence through the chamber 155 and the hole 158 into the upper portion of the vat 13. The defined stream of hot

water impinges on the deflector 163 and is spread or broken up and delivered into the upper portion of the vat 13 through the exit slots 165. The defined stream of hot water that is projected through the central portion of the chamber 155 is spaced well inwardly with respect to the inner end of the vent passage 161 in order to prevent the escape of hot water from the chamber 155 through the vent passage 161. In this construction of the fixture 136, the deflector 163 not only spreads the stream of hot water and delivers it into the upper portion of the vat 13 through the exit slots 165, but it also assists in partially blocking the lower end of the hole 158 in order to prevent the entrance of vapor or steam from the vat 13 back into the chamber 155 and consequently into the vent passage 161 and thence to the atmosphere.

In this form of the fixture 136, it will be understood that in the event of a subatmospheric pressure in the inlet conduit 35, a back-suction will take place through tube 157 between the chambers 155 and 154; however, air is supplied into the chamber 155 via the vent passage 161 and the vent conduit 162 so as to prevent any material back-siphoning of the wash liquid from the upper portion of the vat 13 through the exit slots 165 defined between the nut 145 and the deflector 163; all for the purpose previously explained.

Referring now to Figs. 9 and 10, the other modified form of the fixture 236 there illustrated, and embodying the features of the present invention, comprises an upstanding substantially cylindrical casing 240 terminating adjacent to the lower portion thereof in a substantially cylindrical downwardly extending projection 241. The projection 241 is arranged in the opening 22b formed in the central portion of the boss 22a provided in the top wall 22 of the vat 13; and a liquid-tight connection is made between the casing 240 and the adjacent portion of the boss 22a by an arrangement including upper and lower resilient gaskets 242 and 243 surrounding the opening 22b and respectively arranged above and below the boss 22a. Also a metallic pressure ring 244 engages the gasket 243; and the assembly is retained in place by a nut 245 that is threaded upon the exterior surface of the projection 241. Thus the lower end of the projection 241, as well as the nut 245, the pressure ring 244 and the gasket 243 are disposed below the top wall 22 and within the upper portion of the vat 13.

The casing 240 is hollow and is threaded adjacent to the upper end thereof in order to receive the threaded lower annular flange 246 of an associated hollow cap 247. The upper end of the casing 240 terminates in a substantially annular shoulder 248 that engages and supports the associated annular portion of a partition or diaphragm 249. Specifically the annular portion of the partition 249 is clamped between the shoulder 248 on the casing 240 and an associated annular shoulder 250 provided on the cap 247, a resilient gasket 251 being disposed between the annular portion of the partition 249 and the shoulder 250. The partition 249 divides the interior of the casing 240 and the cap 247 into an upper chamber 254 and a lower chamber 255, the chambers 254 and 255 being disposed primarily respectively within the cap 247 and within the casing 240. The central portion of the partition 249 is upwardly offset into the chamber 254 and is provided with a hole 256 therein that

is arranged in alignment with a hole 257 formed in the lower end of the projection 241, the hole 256 communicating between the chambers 254 and 255 and the hole 257 communicating between the chamber 255 and the upper portion of the vat 13.

A substantially centrally disposed hollow stud 258 is carried by the cap 247 and projects downwardly into the hole 256 in order to define a substantially annular nozzle passage 259 therebetween and communicating between the chambers 254 and 255. Further the nut 245 carries a substantially annular deflector 263 disposed therebelow and connected thereto by a pair of spaced-apart arms 264. Preferably the nut 245, the deflector 263, and the arms 264 are formed of one-piece construction, whereby a pair of oppositely directed exit slots 265 are provided adjacent to the opposite sides of the deflector 263.

Further the fixture 236 comprises a substantially annular upwardly and outwardly directed baffle 266 surrounding the projection 241 and engaging the gasket 242. Specifically the inner annular portion of the baffle 266 is clamped between a shoulder 267 provided on the lower end of the casing 240 and the gasket 242, the compression being provided between the shoulder 267 by the nut 245 threaded upon the lower end of the projection 241. Also the fixture 236 comprises a pair of concentric and nested baffles 268 and 269 secured to an annular flange 270 provided on the lower end of the cap 247 by a plurality of screws 271. The baffles 268 and 269 are arranged in surrounding relation with the casing 240 and extend downwardly into cooperative relation with respect to the baffle 266 in order to provide two substantially concentric annular spaces 272 and 273 surrounding the casing 240. A plurality of radially spaced-apart vent passages 274 are formed in the body of the casing 240 and communicate directly with the annular space 272. Accordingly the baffles 266, 268 and 269 cooperate with each other to define the annular spaces 272 and 273 surrounding the casing 240 and providing a protected communication between the vent passages 274 and the atmosphere. Finally an upstanding substantially cylindrical reticulated screen 275 is arranged in the annular space 272 in surrounding relation with respect to the casing 240, whereby the arrangement of the baffles 266, 268 and 269 and the screen 275 positively protect the vent passages 274 against the entry of foreign material and dust into the chamber 255 in the event of the abnormal condition of a subatmospheric pressure within the chamber 254. Finally the cap 247 is provided with an inlet connection 276 that communicates with the inlet conduit 35 so that hot water may be supplied to the chamber 254.

The operation of the fixture 236 is substantially identical to that of the fixture 36 previously described; and it will be understood that the hot water that is supplied via the inlet conduit 35 into the chamber 254 is projected by the nozzle arrangement through the nozzle passage 259 in a well-defined stream and thence through the chamber 255 and the hole 257 into the upper portion of the vat 13. The defined stream of hot water impinges on the deflector 263 and is spread or broken-up and delivered into the upper portion of the vat 13 through the exit slots 265. The defined stream of hot water that is projected through the central portion of the chamber 255 is spaced well inwardly with respect to the inner ends of the vent passages 274 in order to prevent

the escape of the hot water from the chamber 255 and the vent passages 274 to the atmosphere. In this construction of the fixture 236, the deflector 263 not only spreads the stream of hot water and delivers it into the upper portion of the vat 13 through the exit slots 265, but it also assists in partially blocking the lower end of hole 257 in order to prevent the entrance of vapor or steam from the vat 13 back into the chamber 255 and consequently into the vent passages 274 and thence to the atmosphere.

In this form of the fixture 236, it will be understood that in the event of a subatmospheric pressure in the inlet conduit 35, a back-suction will take place through the nozzle passage 259 between the chambers 254 and 255; however, air is supplied into the chamber 255 via the vent passages 274 so as to prevent any material back-siphoning of the wash liquid from the upper portion of the vat 13 through the exit slots 265 defined between the nut 245 and the deflector 263, all for the purpose previously explained.

Also in this form of the fixture 236, a groove 274' is formed in the bottom of each of the vent passages 274 and communicating with the adjacent annular portion of the baffle 266 so that any liquid that might accumulate in the dish-like baffle 266 as a consequence of the condensation of vapor therein may be returned back into the vat 13 via the hole 257. Also the central portion of the stud 258 depending from the cap 247 is threaded, as indicated at 258', so that the fixture 236 may be converted, if desired, from the arrangement including the deflector 263 to a spinner arrangement. In other words, the deflector arrangement 263 employed in the fixture 236 is identical to the deflector arrangement 163 employed in the fixture 136; and for this arrangement, the spinner arrangement 69 of the fixture 36 may be readily substituted. Thus the fixture 236 may comprise either the deflector arrangement of the fixture 136 or the spinner arrangement of the fixture 36 for the purpose of breaking up and spreading out the defined stream in the upper portion of the vat 13.

In view of the foregoing, it is apparent that there has been provided in dishwashing apparatus, including a vat, an improved combination liquid inlet and anti-back-siphoning fixture, whereby hot water may be readily delivered into the upper portion of the vat without any danger of back-siphoning in the event of the abnormal condition of a subatmospheric pressure in the hot water inlet conduit.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In combination with a liquid receiving vat or the like provided with wall structure having an opening therein disposed above the normal liquid level in said vat, a liquid supply fixture comprising a hollow casing secured in liquid-tight relation with said wall structure about said opening, a partition arranged in said casing and defining first and second chambers therein, said casing having a first hole therein communicating with said second chamber and through said opening with the interior of said vat, said partition having a second hole therein communicating with said first and second chambers, said first

13

and second holes being substantially aligned with respect to each other, a shaft carried by said casing and projecting through said first and second chambers and through said second and first holes and through said opening into said vat, an inlet conduit communicating with said first chamber for normally supplying liquid under gauge pressure thereto, a substantially cylindrical nozzle arranged in said second hole and supported by said partition and surrounding said shaft for projecting liquid from said first chamber in a defined stream along said shaft through said second chamber and said first hole and said opening into the interior of said vat, said casing having a vent passage therein communicating between said second chamber and the atmosphere in order to supply air into said inlet conduit in the event of the abnormal condition of a subatmospheric pressure therein so as positively to prevent back-siphoning of liquid from the interior of said vat into said inlet conduit, said nozzle projecting the liquid stream along said shaft through said second chamber in spaced relation with respect to the inner end of said vent passage in order to prevent the escape of liquid from said second chamber into said vent passage, and a member carried by the inner end of said shaft and arranged within said vat and positioned in the path of the liquid stream for deflecting the liquid from the liquid stream and for spreading the liquid through the interior of said vat.

2. The combination set forth in claim 1, wherein in said member is in the form of a spinner mounted for rotation on the inner end of said shaft and rotated by the force of the liquid stream impinging thereupon.

3. The combination set forth in claim 1, and further comprising a baffle arranged in said second chamber between the liquid stream and the inner end of said vent passage for positively pre-

40

14

venting the escape of liquid from said second chamber into said vent passage.

4. The combination set forth in claim 1, and further comprising a substantially cylindrical baffle carried by said partition and disposed in said second chamber and aligned with said nozzle and surrounding the liquid stream for positively preventing the escape of liquid from said second chamber into said vent passage.

5. The combination set forth in claim 4, wherein in said nozzle and said baffle are formed of one-piece construction and the inner diameter of said baffle is somewhat greater than the inner diameter of said nozzle, and wherein a slot is provided in said construction between said nozzle and said baffle to provide a communication with said second chamber between said nozzle and said baffle.

6. The combination set forth in claim 1, wherein in said hollow casing terminates in a projection arranged in said opening, and further comprises an element carried upon the inner end of said projection within said vat and engaging the adjacent portion of said wall structure for supporting said casing upon said wall structure and for securing said projection in liquid-tight relation with said wall structure.

7. The combination set forth in claim 1, wherein in the vertical distance between the lower end of said nozzle and the bottom of said vent passage is at least 1".
